ATTORNEY

UNITED STATES PATENT OFFICE.

NEVIL MONROE HOPKINS, OF NEW YORK, N. Y.

COLLAPSIBLE TUBE.

Application filed June 11, 1921. Serial No. 476,746.

To all whom it may concern:

Be it known that I, NEVIL MONROE HOPKINS, a citizen of the United States, and a resident of New York city, in the county of New York and State of New York, have invented certain new and useful Improvements in Collapsible Tubes, of which the following is a specification.

This invention relates to collapsible tubes especially adapted to hold tooth pastes and other compounds, and has for its object to provide a device of this character which will be comparatively inexpensive to manufacture and more efficient in use than those heretofore proposed.

With these and other objects in view, the invention consists in the novel details of construction and combinations of parts more fully hereinafter disclosed and particularly pointed out in the claims.

Referring to the accompanying drawings forming a part of this specification, in which like numerals designate like parts in all the views:

25 Figure 1 is a longitudinal sectional view of a collapsible tube made in accordance with this invention;

Figure 2 is a side elevational view of the parts shown in Figure 1; and

30 Figure 3 is a top view and a sectional detail view of a modified form of tube closing structure.

10 represents an inner collapsible container of any suitable material, surrounded by an outer collapsible container 11, and said containers are provided with the usual open ends at their bottoms adapted for folding as indicated at 12 and 13 respectively, all as will be readily understood.

40 The inner tube 10 is further provided with the usual thickened neck portion 14 and the outer tube 11 is provided with the similar neck portion 15.

The inner top member 14 is pierced with a number of holes 16 16 and a hollow neck projecting therefrom screws into the member 15 through the agency of threads shown at 17 until the shoulders 18 are firmly in contact. A screw cap 19 internally threaded at 20 is adapted to engage the threads 21, and carries a downwardly projecting member 22 which travels down with a close fit in the hollow neck of the massive member 14 sharply closing the holes 16, 16, and reaching a position as shown by the dotted line at 23. This downwardly projecting mem-

ber may be slightly tapered as well as the opening which receives it. It is therefore obvious that the cap not only closes the combined orifice 24 of the two concentric tubes but would force back into the inner tube 10 as far as the dotted line 23 any material which may remain in the neck of the member 14 resulting from squeezing the collapsible tubes at or near the bottom folded portions 12 and 13. 25 may be an aqueous paste mixture of barium peroxide and precipitated chalk, and 26 may be an aqueous mixture of a fruit acid and a suitable inert vehicle, and it is evident that these substances may be forced out of the common orifice 24 reacting upon each other as they issue forth and also immediately after having issued forth, liberating nascent hydrogen peroxide, as will appear more fully hereinafter.

With reference to the somewhat modified form of closure shown in Figure 3, the massive top members 26 and 27 of the outer and inner tubes respectively are adapted to screw together at the point 28 against the shoulders 29. The portion 26 is provided with separate orifices of egress 30 for the outside concentric container, and the portion 27 is provided with an independent orifice 31, for the centrally located container. In this said modified construction, the chemical reaction to be described below takes place on the outside of the tube and involves certain advantages over the design illustrated in Figure 1, which is adapted to unite the substances, while issuing from the passage 24, for in this said construction of Figure 3, no quantity of acted upon material is left within a common orifice as is the case with the said design of Figure 1.

Furthermore, when cements and other plastic substances of different properties are employed, the modified design shown in Figure 3 serves best for those cements which set soon after the several ingredients contained in the two tubes have been allowed to react upon each other. In the design shown in Figure 1, on the other hand, such setting of the cement might obstruct the orifice. The screw cover shown in Figure 3 at 32 is provided with a somewhat shorter downwardly projecting lug 33 than is the lug 22 in Figure 1, and the said lug 33 is preferably tapered as shown.

It will now be clear from the above disclosure that I have provided a two compart-

ment collapsible tube adapted to hold a tooth paste consisting of, say, barium peroxide, mixed with precipitated chalk and water in one compartment, and another paste 5 consisting of, say, tartaric acid, or other suitable organic fruit acid, mixed with an inert paste vehicle and water in the other compartment. It is further evident that these two pastes can be kept stable and intact chemically for a given period of time, or until they are caused to flow into contact by collapsing the tubes. When this is done, 10 a germicidal agent consisting of freshly liberated, or nascent hydrogen peroxide will be produced mingled with the precipitated chalk, an inert vehicle, furnishing a carrier for the said germicidal agent, and also a mechanical cleansing means, both of which features are recognized as valuable in a 15 dental paste.

By inert vehicle, I mean a paste forming substance which is not acted upon by the organic or fruit acid with which it is associated. The hydrogen peroxide above mentioned is formed, as is well known, from the barium peroxide present, due to the action 20 of carbonic acid on the barium peroxide, said carbonic acid resulting from the reaction between the tartaric or fruit acid present with the calcium carbonate or precipitated chalk carried by the paste in the presence of water.

It will further be clear that by placing an aqueous paste consisting essentially of 25 BaO_2 in combination with CaCO_3 , in one compartment, and an aqueous paste of tartaric acid mixed with a suitable inert paste making vehicle in the other compartment, the hydrogen peroxide resulting from the 30 mixture of the two pastes is liberated within the mass of precipitated chalk or other inert vehicle, after the mixed pastes reach the tooth brush and also after the mixture is applied to the teeth.

It thus results that the hydrogen peroxide is in its nascent or most active condition when it reaches the film on the teeth, and therefore a better cleansing action is had than it is possible to get with the prior 40 pastes which do not provide this said nascent peroxide. It further will be clear that the liberation of CO_2 gas in the body of the paste while in contact with the teeth of necessity has in addition a greater or less 45 mechanical action in destroying the film, tartar, or other material which is to be removed from the teeth.

It is obvious that those skilled in the art 50 may vary the details of construction of the tubes as well as the ingredients of the pastes employed, without departing from the spirit

of the invention, and therefore I do not wish to be limited to the above disclosure except as may be required by the claims.

What I claim is:

1. A container comprising a plurality of collapsible tubes provided with integral neck portions and located one within the other, substantially as described.

2. A container comprising a plurality of 70 collapsible tubes located one within the other and having a single closure, substantially as described.

3. A container comprising a plurality of concentrically disposed collapsible tubes 75 provided with a single closure, substantially as described.

4. A container comprising a plurality of concentrically disposed collapsible tubes provided with a single outlet and a single 80 closure, substantially as described.

5. A container comprising a plurality of concentrically disposed collapsible tubes provided with a single closure provided with 85 means to enter one of said tubes, substantially as described.

6. A container comprising a plurality of collapsible tubes, associated with each other, and provided with a single closure.

7. A container comprising a plurality of 90 collapsible tubes located one within the other spaced apart and having orifices through the inner tube communicating with the space between the tubes.

8. A container comprising a plurality of 95 spaced collapsible tubes located one within the other provided with a communication between the inner tube and the space between the tubes and having a single closure for both of said tubes.

9. A container comprising a plurality of concentrically disposed spaced collapsible tubes provided with a closure having a depending projection adapted to fit the exit of 100 one of said tubes.

10. A container comprising two collapsible tubes one located within the other and having neck portions provided with outlets adjacent each other, a single removable cap fitting over said neck portions and closing 110 all of said outlets.

11. A container comprising a collapsible tube provided with a restricted neck, a second collapsible tube within the first mentioned tube and also having a restricted 115 neck, the neck of the inner tube being positively secured to the neck of the first mentioned tube.

Signed at New York city in the county of New York and State of New York June 120
A. D. 1921.

NEVIL MONROE HOPKINS.
